CLAIM

The ornamental design of a plaque, as shown and described.

DESCRIPTION

FIG. 1 is a front perspective view of a plaque, showing my new design;

FIG. 2 is a side elevational view thereof, the center broken away for convenience of illustration;

FIG. 3 is an end elevational view thereof;

FIG. 4 is a rear perspective view thereof; and

FIG. 5 is a front elevational view thereof.

FIG. 5
